(57) **CLAIM**

The ornamental design for a bottle holder as shown and described.

DESCRIPTION

FIG. 1 is a front perspective view of a bottle holder;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a cross-sectional view thereof cut along line 9-9 in FIG. 3.

The broken lines in the drawings illustrate portions of the bottle holder, which form no part of the claimed design. The cross-hatching lines in FIG. 9 illustrate the cuts for the cross-sectional view of the bottle holder and form no part of the claimed design.

1 Claim, 9 Drawing Sheets
